(57) **CLAIM**

The ornamental design of a counter-balancing ergonomic body wedge device, as shown and described.

DESCRIPTION

FIG. 1 is a perspective view of a counter-balancing ergonomic body wedge device showing my new design; FIG. 2 is a front view thereof;

FIG. 3 is a rear side view thereof;

FIG. 4 is a left side view thereof;

FIG. 5 is a right view thereof;

FIG. 6 is a top plan view thereof; and,

FIG. 7 is a bottom plan view thereof.

Broken lines in the Figures show the environment of the counter-balancing ergonomic body wedge device, which are not part of the claimed design.
